MAGNET RELEASE FOR GATE DOORS AND
FOR OTHER PURPOSESBryant Steele, Lexington, Ky., assignor to David
E. White, Cleveland, Ohio

Application July 12, 1940, Serial No. 345,219

7 Claims. (Cl. 175—337)

This device relates to a release means for releasing the parts of permanent magnets, constructed for instance of the compositions disclosed in the Ruder patents, Numbers 1,947,274 and 1,968,569; Mishima patents, Numbers 2,027,994 to 2,028,000 inclusive, and the Howe Patent 2,192,743, although the invention is not limited to the use of the compositions disclosed in these patents. Magnets constructed in accordance with the teachings of one or more of these patents have been called by the term of "Alnico metal magnets" or "sintered Alnico metal magnets." These magnets have been of the permanent magnet type, and no means has heretofore been devised to cause the release of the magnetic forces of said magnets.

An object of the present invention is to provide a means for releasing the magnetic forces of, or demagnetizing a permanent magnet, such as an "Alnico metal magnet."

Another object of the invention is to provide a race horse starting gate having doors for the release of the horses provided with permanent magnets, such as magnets of Alnico metal with means for affecting the release of, or demagnetization of the magnets.

Other objects will appear hereinafter.

In the drawings:

Figure 1 is a plan view of a pair of doors of a starting gate provided with the device of my invention.

Figure 2 is a side elevation of a permanent magnet provided with the release device of my invention.

Figure 3 is a top plan view of the device shown in Figure 2, certain parts being shown in section.

Figure 4 is a top plan view of a modification of the device shown in Figures 2 and 3.

Figure 5 is a detail plan view of the magnet block.

Figure 6 is a diagrammatic front elevational view of a horse starting gate, partly broken away.

In the drawings the numeral 1 indicates a mounting block or base preferably constructed of brass, and provided with side plates 2.

The base is provided with a recess 3 for the reception of the magnet block 4 which is retained in the recess in fixed position by suitable means such as screws which are mounted in the side plates.

The magnet block may be made in any suitable manner for holding the Alnico or other magnetic material, but I prefer to construct the same as shown in Figure 5, wherein 6 is a brass or bronze alloy center portion partially surrounded by a

steel or other ferrous metal portion 7 of general horse shoe configuration. The numeral 9 indicates spaces for the reception of brass strips 10 which do not extend all the way to the end of the magnet block at one of their ends, and which connect with or abut the brass center portion at their other ends.

Set into the steel or other ferrous metal portion is the sintered Alnico magnetic plug 8, an alloy composed of aluminum, nickel, iron and cobalt, in accordance with the above enumerated patents.

The side plates 2 mount bearing portions 12 each of which is provided with an elongated slot 13 in which seat the bearings or pins 14 that extend from each side of the secondary short-circuiting armature or release plate 15. This plate is therefore pivotally mounted in the slots 13. The plate is provided adjacent its other end 20 with an upstanding ear 16 having an aperture 17 for the reception of the nose 19 of the latch arm 18 as shown in Figures 2 and 3.

An electro-magnet is indicated at 20 and is provided with a core 21 which when energized 23 pulls the latch arm downwardly (Figure 2), to release the nose from the aperture 17 to thereby permit the spring 22 to force the secondary armature into contact with one side of the magnet block. The spring 22 is mounted on top of the base 1.

The primary armature is designated by the numeral 23. This preferably consists of a central bronze portion 24 having fixedly attached thereto a ferrous metal portion 25 and on the opposite side another ferrous metal portion 26. The ferrous metal portion 25 consists of a series of blocks providing slots 27. Strips of bronze material 28 extend almost to the edge of the slots and connect or abut at their opposite ends with the central bronze portion 24.

The primary armature may be guided in its movements toward the magnet block 4 by a metal strap 29 secured to the side plates 2 by screws 30.

The electro-magnet shown may be of any well known construction and may also be mounted as shown in the alternate construction shown in Figure 4 wherein one of the side plates is indicated at 31. These plates are similar to the plates 2 and are provided with ears 32 having elongated slots 33 in which are mounted the pins 34 forming the pivots for the secondary armature or release plate 35. The electro-magnet is indicated by the numeral 36 and is mounted on the arm 37, which latter is affixed by suitable

means such as a screw 38 to the base 39. The secondary plate is urged to its closed position by the spring 40 which is mounted on the base by means of the screw 41. The electro-magnet is provided with a core 42.

The primary armature is indicated by the numeral 43. This armature is the same or similar to that disclosed in Figures 2 and 3 and may be guided towards the magnet block, which is not illustrated but which is the same as that shown in Figure 3, by the strap 44 which is affixed to the base by screws 45.

I have shown in Figure 1 one use to which my invention may be applied. The numerals 46 and 47 indicate pivoted doors of the type illustrated at 14 in my patent, No. 2,193,257, granted March 12, 1940. As illustrated the primary armature 23 is mounted on a supporting strap 48 connected adjacent to the end of the door 46. The magnet and release shown in Figures 2 and 3 are mounted adjacent to the juxtaposed end of the other door 47. The electro-magnet 20 is mounted on an arm 49 which is also affixed to the door 47. The electromagnet indicated in Figures 2 and 3, or Figure 4 is connected into the circuit 50 (Figure 1). This circuit has a source 51 and an electrical switch 52.

The primary armature 23 will be released from the magnet block 4 as follows: actuation of the switch 52 energizes the electro-magnet which attracts the armature pulling latch arm 18 downwardly as shown in Figure 2, thus moving the nose 19 of said arm 18 out of the aperture 17. The release plate 15 is now free under the action of spring 22 to move to its closed position against the Alnico magnet block 4. The magnetic flux which has passed through the primary armature from the magnet will now be diverted or shunted and will now pass through the plate 15. In other words the flux path will pass through the plate 15 instead of passing through the primary armature 23. When this occurs the springs tending to open the doors 46 and 47 (shown in Figure 3 my prior patent above) will immediately cause the opening of said pair of doors in the same manner as described in my patent. It is to be understood that there are as many pairs of doors for magnets as shown in Figure 1 as there are pairs of stall partitions. It is of course obvious also that each magnet may be controlled from a single circuit as indicated in Figure 5 of my patent.

Figure 6 shows another manner of applying my invention to a starting gate for race tracks. In the figures 54 and 55 indicate vertical posts pivotally mounted to the superstructure 53 and partitions 62 and 63. Rigidly mounted on these posts so as to swing therewith are the doors 56 and 57.

The arms 58 and 59 are rigidly mounted on the posts 54 and 55 respectively and swing therewith. When the doors are in closed position as indicated in the figure the magnet 60 mounted on the arm 58 and the primary armature 61 mounted on the arm 59 contact each other and hold the pair of doors 56 and 57 in closed position until the electro-magnet is operated to release the armature 61 from the magnet 60. The doors are opened by springs not shown but as indicated in Figure 3, my former patent above referred to. The magnet, and electro-magnet diagrammatically illustrated in Figure 6 are the same in detail as that disclosed in Figures 2, 3 or 4 of this application.

It will be noted that in the structure shown

by Figures 2 and 3 the secondary armature is held in its open position by the latch 18 until the current is turned on. When the current is turned on the latch arm 18 is drawn downwardly to release the said secondary armature. In Figure 4 however no latch is provided, and the secondary armature 35 is retained in its open position as long as the current is on so that the core 42 is energized by current in the magnet 36.

10 It is to be understood that the term "electro-magnet means" in the claims refers to the parts 18, 19 and 20 shown in Figures 2 and 3, or the parts 36 and 42 in Figure 4.

15 It is to be understood that the device of the present invention may be used not only on gates for starting horses at a race track, but that the magnet release of this invention may be used for any purpose to which it is applicable. Other uses to which my invention may be put include this application for use with a magnetic chuck, or in fact any use which includes a permanent magnet or an electro-magnet.

I claim:

25 1. In combination, a permanent magnet, a primary armature therefor normally held by the flux of the permanent magnet in substantial contact therewith, shunting means for shunting magnetic flux away from said primary armature including a secondary armature adapted for movement toward and away from said magnet, spring means for urging said secondary armature towards said magnet, latch means for retaining said secondary armature out of contact with said magnet to prevent movement of said armature by said spring means, and electro-magnetic means for operating said latch means to thereby release said secondary armature when said electro-magnetic means is energized.

40 2. In combination, a permanent magnet, a primary armature therefor normally held by the flux of the permanent magnet in substantial contact therewith, shunting means for shunting magnetic flux away from said primary armature including a secondary armature pivotally mounted on said permanent magnet adapted for movement toward and away from said magnet, spring means for urging said secondary armature toward said magnet, latch means for retaining said secondary armature out of contact with said magnet to prevent movement of said armature by said spring means, and electro-magnetic means for operating said latch means to thereby release said secondary armature when said electro-magnetic means is energized.

45 3. In combination, a permanent magnet, a primary armature therefor normally held by the flux of the permanent magnet in substantial contact therewith, shunting means for shunting magnetic flux away from said primary armature including a secondary armature adapted for movement toward and away from said magnet, biasing means for urging said secondary armature towards said magnet, and electro-magnetic means for retaining said secondary armature in a position away from said magnet when said electro-magnetic means is energized.

50 4. In combination, a permanent magnet, a primary armature therefor normally held by the flux of the permanent magnet in substantial contact therewith, shunting means for shunting magnetic flux away from said primary armature including a secondary armature pivotally mounted on said permanent magnet adapted for movement toward and away from said magnet, biasing means for urging said secondary armature into contact with

said magnet, and electro-magnetic means for retaining said secondary armature in a position away from said magnet when said electro-magnetic means is energized.

5. In combination, a permanent magnet, including a part composed of an alloy of aluminum, nickel, iron and cobalt, a primary armature therefor normally held by the flux of the permanent magnet in substantial contact therewith, a secondary armature mounted on said magnet for movement into contact with or away from said magnet, means normally urging said secondary armature into contact with said magnet, and electro-magnetic means located adjacent to said secondary armature for holding said secondary armature away from said magnet when the electro-magnetic means is energized.

6. In combination, a releasable permanent magnet, a primary armature for said magnet responsive to the flux thereof and adapted to move toward and away from said magnet in a longitudinal direction thereof, a secondary armature mounted on said magnet and adapted to move in

a transverse direction to that of said primary armature, means biasing said secondary armature into contact with said magnet, and electro-magnetic means for retaining said secondary armature in a position out of contact with said magnet.

7. In a device of the character described, a permanent magnet, a primary armature therefor normally held by the flux of the permanent magnet in substantial contact therewith, means biasing the primary armature to move away from the permanent magnet upon reduction of said flux through the primary armature, a secondary armature mounted for movement toward the permanent magnet to shunt the flux thereof through the secondary armature and thereby reduce the flux through the primary armature and for movement away from the permanent magnet, means biasing the secondary armature to move toward the permanent magnet, and electro-magnetic means for controlling the movement of the secondary armature.

BRYANT STEELE.
